UNITED STATES PATENT OFFICE

FÉLICIE EUGÉNIE AMÉLIE WANPOUILLE BERGAUD, OF PARIS, FRANCE

DESIGN FOR A VANITY CASE OR THE LIKE

Application filed March 14, 1933. Serial No. 47,444. Term of patent 14 years.

To all whom it may concern:

Be it known that I, FÉLICIE EUGÉNIE AMÉLIE WANPOUILLE BERGAUD, a citizen of the French Republic, residing at 10 rue de la Paix, Paris, France, have invented a new, original, and ornamental Design for a Vanity Case or the like, of which the following is a specification, reference being had to the accompanying drawing, forming part thereof.

Fig. 1 is a front perspective view of a vanity case or the like, showing my new design, and

Fig. 2 is a rear perspective view thereof.

I claim:

The ornamental design for a vanity case or the like, as shown.

FÉLICIE EUGÉNIE AMÉLIE WANPOUILLE BERGAUD
